UNITED STATES PATENT OFFICE.

JOSEPH J. STEFFAN AND CORNELIUS G. SCILLIGO, OF ST. LOUIS, MISSOURI.

SCREEN.

1,235,735.

Specification of Letters Patent.

Patented Aug. 7, 1917.

Application filed May 17, 1915. Serial No. 28,564.

To all whom it may concern:

Be it known that we, JOSEPH J. STEFFAN and CORNELIUS G. SCILLIGO, citizens of the United States of America, and residents of the city of St. Louis, State of Missouri, have invented certain new and useful Improvements in Screens, of which the following is a full, clear, and exact description, reference being had to the accompanying drawing, forming a part of this specification.

Our invention relates to a screen comprising a frame and a sheet of screen cloth secured to said frame, the main object being to produce a very strong sheet metal screen frame.

The preferred form of the invention comprises frame pieces each of which is a single sheet of metal folded on itself to produce two metallic layers, one of which we term a back member and the other a reinforcing member. The longitudinal margins of the metal are preferably folded to reinforce the longitudinal margins of the frame piece, and the reinforcing member is preferably pressed between said margins to produce a longitudinal reinforcing web. By folding, pressing and otherwise bending the metal as will be hereinafter described, we produce a very strong screen frame which is not liable to bend or become distorted by the stresses it receives in service.

Figure I is a fragmentary front elevation, illustrating a corner portion of a screen embodying the features of our invention.

Fig. II is a rear elevation of the structure shown in Fig. I.

Fig. III is a detail view of an end portion of one of the frame pieces.

Fig. IV is an enlarged cross section taken through one of the frame pieces, showing a portion of the screen and the means for securing the screen.

The frame structure comprises sheet metal frame pieces A, arranged at right angles to each other and connected together at the corners of the screen by means of rivets 1, or other suitable fastening devices. Each frame piece A is preferably a single piece of sheet metal folded on itself to produce a back member 2, a reinforcing member 3, a tubular bead 4 at the outer margin of the frame piece, and a screen receiving channel 5 at the inner margin of the frame piece.

The screen receiving channel 5 is preferably

formed by folding the two layers of metal backwardly and inwardly to produce the doubled reinforcing element 6. The inner margin of each frame piece is very materially reinforced by folding the terminals of the folded sheet of metal; and owing to the curvature of the metal at the fold the screen cloth B will slide freely over the inner margin of the frame piece when said screen cloth is forced into the channel 5. The screen is pulled firmly and stretched slightly while its margins are being forced into the screen receiving channels 5, and it is an advantage to pull the screen over the curved edge of the doubled reinforcing element 6, instead of pulling it over a narrow edge on a sharp corner.

In applying the screen cloth B to the frame, the margins of the screen cloth are forced into the channels 5 by means of retaining strips C. Each retaining strip is preferably a sheet metal clip having a longitudinal detent flange 7, yieldingly fitted to the inner face of the tubular bead 4, and having a body portion 8 which extends from said detent flange to a screen receiving channel 5. The screen cloth is pulled firmly while the retaining strip is being forced into the screen receiving channel, and thereafter the retainer strip is shifted from the position shown by dotted lines (Fig. IV) to the position shown in full lines, thereby securing the screen to the frame. The retaining member C may be readily removed by releasing its yieldable detent flange 7 from the tubular bead 4 and then withdrawing the inner edge of the retaining member from the screen receiving channel.

In addition to reinforcing each frame piece at its longitudinal margins, by means of the bead 4 and double curl 6, we preferably reinforce the middle portion of the structure by pressing the reinforcing member 3 away from the back member 2 as shown in Fig. IV. The reinforcing member 3 is preferably bowed at this point to provide a rigid reinforcing web which extends almost entirely across the frame piece.

The back member 2 is preferably pressed inwardly, toward the reinforcing member 3, to produce a series of angular ribs 10. These ribs 10 lie between the reinforced margins of the frame piece, and they are preferably integrally connected together to form a long zig-zag reinforcing element.

The curled margins 6 are preferably pro-

vided with indentations 12, the metal of the outer curled element being forced into the indentations in the inner curled element so as to securely interlock these elements with each other. The object of interlocking the layers of metal at this point is to positively prevent one layer from slipping on the other. When a frame piece is subjected to a twisting or torsional strain one of the 10 layers of metal tends to slip on the other, and by preventing such slippage the resistance offered to the torsional strains is very materially increased.

The end portions of each frame piece are 15 preferably formed as shown in Fig. III, the double curl 6, the bead 4 and the reinforcing member 3 being cut away to coincide with the corresponding parts of another frame piece. 18 designates an L-shaped corner 20 rod inserted into the tubular beads 4, and 14 is a corner member inserted between the back member 2 and the bowed reinforcing web 3.

15 designates a friction spring secured to 25 a vertical edge of the screen frame and adapted to engage the window casing (not shown) when the screen is in service. One end of the spring 15 is inserted into an opening 16 in the tubular bead 4 so as to 30 lie between the angular corner member 13 and the inner face of said tubular bead, the member 13 serving as means for securing the spring to the screen frame. The free 35 end of the spring 15 is adapted to slide on the vertical edge of the frame piece, and the middle portion of the spring is bowed away from said frame piece so as to frictionally engage the window casing.

We claim:

- 40 1. A screen having frame pieces each of which comprises a single sheet of metal folded on itself to provide two layers of metal, the inner margins of both layers being turned backwardly and inwardly to provide
- 45 a two ply reinforcing element and a screen receiving channel, a sheet of screen cloth fitted to said frame pieces, and means for forcing the margins of said screen cloth into the screen receiving channels.
- 50 2. A screen having frame pieces each of which comprises a sheet metal back member and a sheet metal reinforcing member formed integral with one longitudinal margin and secured to the other longitudinal 55 margin of said back member, said sheet metal reinforcing member being separated from said back member at a point between said margins so as to form an intermediate reinforcing web, a sheet of screen cloth fitted to said frame pieces, and retainer strips arranged over the reinforcing members to secure the screen cloth to said frame pieces.
- 60 3. A screen having frame pieces each of

which comprises a sheet of metal folded on itself to form a back member and a reinforcing web, the outer margin of said sheet of metal being bowed to produce a marginal reinforcing element, the inner margin being bent to provide a reinforcing element and a screen receiving channel, and the middle 70 portion of said reinforcing web being bowed from said back member, a sheet of screen cloth fitted to the inner margins of said frame pieces, and retainer members arranged over the bowed portions of the said 75 reinforcing webs and fitted to the marginal portions of said frame pieces to secure the screen in the screen receiving channels.

4. A screen having frame pieces each of which comprises two layers of metal fitted 80 to each other and folded to produce a double reinforcing element, the folded portions being indented to interlock said layers with each other, a sheet of screen cloth fitted to said frame pieces, and means for securing 85 said screen cloth.

5. A screen having frame pieces each of which comprises two layers of metal fitted to each other and curled backwardly at their 90 inner margins to provide a screen receiving channel, the curled portions of said metal being indented to interlock them with each other, a sheet of screen cloth, and means for securing said screen cloth in said screen receiving channels.

6. A screen having frame pieces each of which comprises a sheet metal back member bent to form longitudinal reinforcing elements at its longitudinal margins, and pressed inwardly between said marginal reinforcing elements to produce a series of diagonal reinforcing ribs, a sheet of screen cloth, and means for securing said screen cloth to said frame pieces.

7. A screen frame having an opening in 105 one of its side edges, a friction spring having one of its ends arranged in said opening, and a fastening device for securing said end of the spring in said opening, the opposite end portion of said spring being slidably fitted to the outer face of said side edge 110 of the frame, and the middle portion of said spring being bowed away from said frame.

8. A screen frame having a tubular marginal portion, a bow spring fitted to a vertical edge of said tubular marginal portion, one end of said spring being arranged in said tubular marginal portion, and a corner member arranged in said tubular marginal portion so as to secure said end of the 115 spring, the opposite end portion of said spring being slidably fitted to the frame and the middle portion of said spring being bowed from the frame.

JOSEPH J. STEFFAN.
CORNELIUS G. SCILLIGO.
